NORMAN W. STORER, OF PITTSBURGH, PENNSYLVANIA, ASSIGNOR TO WESTINGHOUSE ELECTRIC & MANUFACTURING COMPANY, A CORPORATION OF PENNSYLVANIA.

MEANS FOR MINIMIZING COMMUTATOR FLASHOVERS.

1,412,546.

Specification of Letters Patent. Patented Apr. 11, 1922.

Application filed October 30, 1918. Serial No. 260,292.

To all whom it may concern:

Be it known that I, NORMAN W. STORER, a citizen of the United States, and a resident of Pittsburgh, in the county of Allegheny and State of Pennsylvania, have invented a new and useful Improvement in Means for Minimizing Commutator Flashovers, of which the following is a specification.

My invention relates to means for minimizing flashovers, and it has for its object to provide apparatus of the character designated that may be quickly and inexpensively applied to old machines as well as to new machines and which shall be effective in operation, even under severe working conditions.

The single figure of the accompanying drawing is a diagrammatic view of a dynamo-electric machine, together with auxiliary apparatus embodying a preferred form of my invention.

Flashovers are of more or less frequency on the commutators of dynamo-electric machines, particularly in machines of the high-voltage type. This phenomenon is initiated by exceptionally severe overloads or by abrupt changes in load, the resultant excessive armature-reactance voltage initiating sparks between commutator segments and between segments and the brush, these incipient sparks being carried around the commutator to a brush set of the other polarity, ionizing a path between brush sets of opposite polarity and, therefore, permitting a direct discharge therebetween, with consequent severe injury to the apparatus. The principal source of energy for the maintenance of the violent flashover arc is the stored energy of the armature and of the magnetic field circuit, the collapse of these magnetic fields liberating energy at a high rate.

It is, of course, true that a certain amount of the flashover energy flows in from the system, particularly where the machine is operating in parallel with other machines, but the ordinary breakers generally limit the amount of energy received from this source to a relatively small amount.

I find that, if a discharge gap be connected between brush sets of opposite polarity or between the terminals of a machine, this dis-

charge gap being mounted in proximity to the commutator surface, the occurrence of a flashover ionizes the gap, initiating a heavy current discharge between the terminals of the machine, this short-circuit path rapidly dissipating the stored energy of the machine as well as furnishing a shunt path around the machine for energy tending to flow in from the system prior to the opening of the breakers. Preferably, the discharge gap is placed immediately behind the brush set so that the incipient sparks tending to produce a flashover shall also ionize the gap.

Furthermore, I find that an extremely beneficial effect may be produced by providing an auxiliary winding on the field pole pieces, this winding being connected in series with said discharge gap and being so wound that the flow of current through the gap, upon the occurrence of a flashover, causes the auxiliary winding to magnetically oppose the regular exciting field windings, thereby rapidly killing the field and inductively absorbing its stored energy, thus radically reducing the energy available for the maintenance of the flashover arc.

Referring to the drawing for a more detailed understanding of my invention, I show a dynamo-electric machine of the commutator type at 1, this machine comprising an armature 2, an exciting field pole piece 3, and brushes 4, these brushes bearing on a commutator cylinder of usual form 5. The machine 1 may be either a motor or a generator and is shown as connected between a positive feeder 6, such as a railway trolley wire and ground at 7.

The field pole piece 3 is provided with an exciting winding 8, shown as of the shunt type, and with an auxiliary winding 9.

A discharge gap 10 is mounted in proximity to one of the brushes, preferably on the following side thereof, and comprises 95 horn members 11 and 12, the shortest portion of the discharge gap being in immediate proximity to the surface of the commutator cylinder 5. The discharge gap 10 is connected between the brushes 4—4 through the 100 auxiliary field winding 9 and a resistor 13, this latter element being necessary only in certain cases.

Having thus described the arrangement

of a system embodying my invention, the operation thereof is as follows. Under normal conditions, the gap 10 is non-conducting and the winding 9 is not energized, the exciting field for the machine 1 being provided by the field winding 8.

Upon the occurrence of abnormal load conditions, severe sparking occurs at the heels of the brushes 4-4, tending to establish a flashover. These incipient sparks ionize the discharge gap 10 so that, simultaneously with the initiation of a flashover, current flow takes place across the gap 10 and through the winding 9, this current flow being in such direction that the winding 9 magnetically opposes the winding 8, immediately "killing" the excitation of the machine. The stored energy of the armature is at once dissipated by the circuit conditions established across its terminals, and the stored energy of the field circuits is likewise eliminated so that the disastrous effects of the flashover are largely prevented, the flow of current from the line being abruptly stopped by the opening of a circuit-breaker 14.

While I have shown my invention in its preferred form, it will be obvious to those skilled in the art that it is not so limited but is susceptible of various minor changes and modifications without departing from the spirit thereof, and I desire, therefore, that only such limitations shall be placed thereupon as are imposed by the prior art or are specifically set forth in the appended claims.

I claim as my invention:

1. The combination with a dynamo-electric machine of the commutator type, of means mounted thereon providing a discharge gap, and connecting means for inserting said gap between the terminals of said machine.

2. The combination with a dynamo-electric machine of the commutator type, of means providing a discharge gap, connecting means for inserting said gap between the terminals of said machine, said gap providing means being disposed adjacent to the commutator cylinder of said machine.

3. The combination with a dynamo-electric machine of the commutator type, of means providing a discharge gap, connecting means for inserting said gap between the terminals of said machine, said discharge gap being mounted in proximity to the surface of the commutating segments, whereby it is ionized and a discharge thereacross initiated upon the occurrence of a flashover on the commutator of said machine.

4. The combination with a dynamo-electric machine of the commutator type, of means providing a discharge gap, connecting means for inserting said gap between the terminals of said machine, said discharge

gap being mounted in proximity to the surface of the commutating segments and at a point immediately behind a brush set, whereby, upon the occurrence of an incipient flashover at said commutator, said gap will be ionized and a discharge thereacross initiated.

5. The combination with a dynamo-electric machine of the commutator type provided with an exciting field winding, of means providing a magnetomotive force opposed to the magnetomotive force of said field winding and operative only upon the occurrence of a flashover at the commutator of said machine.

6. The combination with a dynamo-electric machine of the commutator type provided with field-exciting means, of an auxiliary stator field winding in electrical alignment with said field-exciting means, and means for energizing said auxiliary field winding so as to magnetically oppose said field exciting means upon the occurrence of a flashover in said machine.

7. The combination with a dynamo-electric machine of the commutator type provided with field exciting means, of an auxiliary field winding in magnetic alignment with said field exciting means, means providing a discharge gap, connections for inserting said discharge gap between two brush sets of opposite polarity in said machine and in series relation with said auxiliary field winding, and means whereby said discharge gap is ionized and a discharge initiated thereacross upon the occurrence of an incipient flashover in said machine, the consequent direction of current flow in said auxiliary field being such as to demagnetize said field exciting means.

8. The combination with a dynamo-electric machine of the commutator type provided with a field-pole bearing an exciting field winding and an auxiliary field winding, of means provided with a discharge gap disposed in proximity to the surface of the commutating segments in said machine, and connections from one terminal of said machine through said gap providing means and auxiliary winding to the remaining terminal of said machine, whereby, upon the occurrence of a flashover at the commutator of said machine, current flow is initiated through said auxiliary winding, said current flow being in such direction as to cause said auxiliary winding to magnetically oppose said exciting field winding.

9. The combination with a dynamo-electric machine of the commutator type provided with a field-pole bearing an exciting field winding and an auxiliary field winding, of means providing a discharge-gap in proximity to the surface of the commutating segments in said machine immediately behind a

brush-set, said connections from one terminal of said machine through said gap and auxiliary winding to the remaining terminal of said machine, whereby, upon the occurrence of an incipient flashover at the commutator of said machine, current flow is initiated through said auxiliary winding, said

current flow being in such direction as to cause said auxiliary winding to magnetically oppose said exciting field winding. 10

In testimony whereof, I have hereunto subscribed my name this 26th day of Oct. 1918.

NORMAN W. STORER.
